UNITED STATES PATENT OFFICE.

PERCY LEWIS BRAUNWORTH, OF BLOOMFIELD, NEW JERSEY.

SECTIONAL BUILDING.

Application filed February 7, 1925. Serial No. 7,618.

The present invention relates to new and useful improvements in building constructions, and it pertains more particularly to a building of the sectional type.

5 It is one of the primary objects of the present invention to provide a new and improved form of sectional building, the construction of which will facilitate the erection thereof.

10 It is another object of the invention to employ sections which will readily fit together to form the completed building.

It is a further object of the invention to provide means for securing the sections together to retain them in proper position.

15 Another object of the invention is to provide a plurality of open building sections and to set them up in the field in this condition, after which the surface or wall covering is placed thereon.

With the above and other objects in view, reference is had to the accompanying drawings, in which—

20 Figure 1 is a perspective view of a building frame construction in accordance with the present invention;

Fig. 2 is a view in elevation of one of the elements of the building frame, the element being shown partly in section;

25 Fig. 3 is a detail view, partly in elevation and partly in section, showing the manner in which two or more of the elements are secured together and also showing the means by which the cap plate is secured to the elements;

30 Fig. 4 is a detail sectional view showing the manner in which the cap plate is secured to the elements and the manner in which the roof beams are supported;

Fig. 5 is a detail sectional view taken on the line 5—5 of Fig. 3;

40 Fig. 6 is a detail sectional view showing the manner of securing the corner sections together;

Fig. 7 is a detail sectional view taken on the line 7—7 of Fig. 3;

Fig. 8 is a detail sectional view taken on the line 8—8 of Fig. 6;

Fig. 9 is a detail view partly in elevation and partly in section, showing the manner of securing the building sections to the sill;

Fig. 10 is a view partly in elevation and partly in section, showing a building frame in which the building is of the gable-roof type;

Fig. 11 is a detail view partly in elevation

and partly in section, showing a modified form of front construction;

Fig. 12 is a detail view partly in section of one of the framing braces used in forming a gable roof.

In carrying out the invention, a plurality of previously formed sections are employed to form the walls of the building, and, as more clearly shown in Fig. 2, each of these sections comprises a monolithic structure including a frame 10, two of the sides of which are connected by a cementitious structure 11. Each of the members 11 is provided with one or more reinforcing elements 12, and each of these reinforcing elements extends preferably throughout the length of its respective member 11. The reinforcing elements 12 of the members 11 extend into the frame as designated by the reference 75 numeral 13, and form the reinforcement of the frame or unit.

The frame is provided at various points with openings 14, as more clearly shown in Figs. 5 to 9, inclusive, and these openings 80 form means for securing the sections together. The openings 14 are adapted to receive bolts 23 by which the sections are secured together.

As shown in Fig. 1, certain of the sections may be formed with openings 18 for the reception of windows, and by such construction, inasmuch as the sections are interchangeable, the sections may be positioned in the building to locate the windows 90 at any point desired.

In carrying out the invention, a sill 20 is employed, and the sections are placed upon the sill as shown in Fig. 1. The sill may be of concrete or lumber, and it serves as a 95 template and a strengthening device at the same time. Where the sill is of ordinary lumber construction, such for example, as a two by four, or of reinforced concrete, the sections are secured to the sill by means of 100 bolts or the like passing through the openings 14 in the bottom edge thereof.

Referring to Fig. 5, it will be noted that where the sections end or abut each other, they are secured together by means of 105 straight bolts 23, which pass through the openings 14, and when the nuts on these bolts are tightened the sections will be securely held in position.

At that point where the sections meet to 110 form the corners of the building, a different type of fastener is employed. At this point

one of the sections is provided with a straight bolt 25, which passes through the opening 14, and the other section is provided with an eye-bolt 26, the eye of which 5 is adapted to receive the straight bolt 25, and when the several nuts are tightened the corner structure will be complete.

Referring to Figs. 3 and 4, the reference numeral 30 designates a cap plate, and such 10 cap plate is adapted to receive and support the roof beams 31. The cap plate is secured to the units 10 by bolts 26', which pass through certain of the openings 14 heretofore mentioned. If the cap plate is of a cementitious material, such as designated by the 15 numeral 32 in Fig. 4, it will have openings, such as 35, to receive bolts 36, by means of which it may be bolted to the sections.

Sections are employed at the front of the 20 building, or in lieu thereof, heavy corner posts, such as designated by the reference numeral 50, upon which to swing the doors, are provided, and a center section or post, or style, 51, is employed to support the cap 25 plate intermediate of its ends, said center post 51 resting upon the sill 20. This construction divides the front wall of the building into two spaces which are adapted to be closed by doors. The corner posts 50 30 are provided with openings 52, by means of which the hinges of the doors are attached to the front sections.

From the foregoing it is apparent that the 35 present invention provides a new and improved method of forming buildings, by means of which a plurality of open sections or units of standard sizes may be associated together for the purpose of forming a complete frame structure. Furthermore, the invention provides means whereby the several 40 sections employed may be cast from cementitious material and secured together without damage to the sections. These open sections are adapted to be set up on the job, and after 45 they are thus set up and connected, the covering for the building, such as lathe, shingles, timber, etc., can be put on readily.

After the framing of the building is up, a suitable roof, such as 40, may be secured 50 in any manner to the roof beams 31, the construction readily lending itself to any type of roof, such as hip, ridge, hip and ridge, or gable. Settings may be made for the roof of the same as for the side walls, if 55 desired.

Referring to Figs. 10 and 12, it will be noted that the framing comprises sections secured upon the sills in the same manner as described in connection with Figs. 1 and 60 9. The gable roof, however, in this form comprises triangular members 60, two sides of which are abutted as designated at 61, and secured together by means of bolts or the like, 62, as heretofore described. Referring to Fig. 12, it will be noted that each of 65

these triangular roof braces has a plurality of transversely extending web members 63. As designated by the reference numeral 64, the reinforcing elements of these roof braces are substantially rectangular in form 70 and independent, there being one in each end member of the rectangle and two in each of the transverse webs 63, as shown in dotted lines in said figure. By this construction, each of the roof braces is divided 75 into a plurality of spaces, and each space is strengthened by its reinforcement 64 which extends therearound. These roof braces are provided with suitable openings 65, by means of which they may be secured 80 together at their meeting faces by the bolts 62 heretofore mentioned. It is intended that short gables may be cast in one section and longer gables in two or more sections.

Fig. 11 shows a new and improved front 85 section construction for use with any type of building, and this construction is employed where it is necessary to use doors of relatively narrow width. This form of front section comprises side members 70 connected 90 by a center stile or the like, 71, and end members 72. The reference numeral 73 designates a filler section which is secured to the end members 72 by bolts 74, and this filler section 73 has blocks or the like 75, to 95 which the door hinges are adapted to be secured.

When the framing has been completed the outer surface thereof may be covered with any desired material, such as stucco, and 100 the inner surface may be lined, if desired, the method of fastening of which forms no particular part of the present invention.

In lieu of forming the several units of 105 the building with openings for the reception of bolts to secure the units together, it is obvious that the cementitious structure may be of a type which permits of the driving of nails thereinto, in which event 110 the several units will be nailed together. It will also be noted that the openings through which the several bolts are passed are of an elongated nature which permits 115 of the proper positioning of the bolts relative to the units in securing them together.

What is claimed is:

A sectional building unit comprising a substantially rectangular frame, division members connecting two of the sides of said frame and dividing the same into a plurality of substantially rectangular spaces, reinforcing elements embedded in the division members and extending into the frame, each of said reinforcing elements being continuous in itself and surrounding one of said spaces, and means for securing a plurality of said units together to form 120 a building.

PERCY LEWIS BRAUNWORTH.
